UNITED STATES PATENT OFFICE.

HUGO V. STEUERNAGEL, OF HARTFORD, CONNECTICUT.

SWINGING-STRUCTURE MOUNT.

1,115,345.

Specification of Letters Patent.

Patented Oct. 27, 1914.

Application filed March 9, 1914. Serial No. 823,378.

To all whom it may concern:

Be it known that I, HUGO V. STEUERNAGEL, a subject of the Emperor of Germany, residing at Hartford, in the county of Hartford and State of Connecticut, have invented certain new and useful Improvements in Swinging-Structure Mounts, of which the following is a specification.

This invention relates to what I shall term for convenience "a swinging structure mount." The swinging structure as may be inferred, may take the form of a door, a gate, a window, a flap or something of an analogous character. The supporting-body for the swinging member of whatever nature the same may be, may vary decidedly in nature, depending upon the particular use to which the article is to be put. I have found the invention as highly advantageous when incorporated in or forming part of a cabinet or box such as used in sectional book-case equipment and with show cases. The swinging element may move in any desired direction; that is it may move horizontally, vertically or obliquely to either of the other directions.

One of the primary objects of the invention is the provision of an article of the character described by which a swinging member such for instance as a door, can be effectively mounted and can be opened or closed without binding in either direction and with a minimum expenditure of power.

The device possesses other features of novelty and advantage, which with the foregoing will be stated at length in the following description wherein I will set forth in detail that form of the embodiment of the invention which I have selected for illustration in the drawings accompanying and forming part of the present specification. I do not limit myself to this disclosure; I may depart therefrom in several particulars within the scope of the invention defined by the claims following said description.

Referring to said drawings: Figure 1 is a sectional view on the line 1—1 of Fig. 5, looking in the direction of the arrow, the swinging element represented as a door, being shown in the upper dotted line position in its maximum open position and in the lower dotted line position as being dismounted. Fig. 2 is a practically similar view showing the door also dotted and as occupying an intermediate position. Fig. 3

is a cross section on the line 3—3 of Fig. 2, looking in the direction of the arrow. Fig. 4 is an end elevation of a cabinet or show case equipped with a mount involving the invention. Fig. 5 is a front elevation of the same.

Like characters refer to like parts throughout the several views, which are on different scales.

As already noted I can use the invention in widely-different connections. In Figs. 4 and 5 I have shown a cabinet 2 presenting a suitable supporting body for the swinging part 3 which as shown consists of a door adapted when shut to close the open front side of the cabinet or case 2 and when open to uncover said opening as will hereinafter more particularly appear. The cabinet or case 2 need not set as shown. It can be arranged so that what is now the back in Fig. 4 would present the bottom, and in this event the door 3 or equivalent part would be at the top. In other words I wish to make it clear that I do not limit myself to any particular disposition of the door or equivalent, and I have cited two of many illustrations in which the same can be arranged to swing.

The swinging member is provided with laterally-extending studs and the supporting body has grooves to receive the studs, the grooves being so shaped as to jointly apply a camming and guiding action to and to also properly support the swinging member whether the same be in the form of a door or otherwise. Preferably the studs are duplicated at opposite ends of the door and necessarily the grooves are also duplicated, each groove being adapted to receive a stud or projection. The construction of the studs is not a matter of consequence. As shown they are plain, but they might be provided with anti-friction rollers or equivalent means, the invention not concerning these and similar details.

On what is shown as the ends of the door 3 are studs or projections 4 and 5, 6 and 7, there being as shown two of each studs at each end of the door, and while these studs may be cross sectionally of any suitable form, the best results are obtained by making them practically cylindrical. In the present instance the stud 5 is alined with the stud 4, and the stud 7 is alined with the stud 6 depthwise of the door. Within

the cabinet or case 2 and in opposite walls thereof, (the end walls as shown) are cam and guiding grooves 8 and 9, 10 and 11, the grooves 8 and 10 being mates and being 5 directly opposite each other, while the grooves 9 and 11 are alike and are also opposed. The grooves 8 and 10 receive for sliding movement the pins or studs 4 and 6, while the longer grooves 9 and 11 receive 10 for corresponding motion the pins or studs 5 and 7. As illustrated both grooves are of cam shape and as also having ineffective portions, so that the walls of one pair of opposite grooves may at one time be performing 15 a camming action, while simultaneously the walls of the other two grooves may be simply guiding and vice versa. The shape of the two grooves may be varied decidedly. As shown the grooves 8 and 10 20 are formed first on an arc which merges into an arc of still greater radius, the inner terminal portions of said grooves being projected at an angle to the respective bodies and the said projecting portions being open 25 as at 12 for a reason that will be hereinafter described. With the grooves 9 and 11 they first have a descending portion 9', then they merge into the arcuate portion of large radius and finally extend at right angles to 30 the major part of their length being also open as at 13. The purpose of the open inner ends 12 and 13 of the two sets of grooves is to facilitate the dismounting of the swinging part 3 as will hereinafter appear. 35

Normally or when the door 3 is closed the two sets of pins 4 and 5 and 6 and 7 will be at the forward or closed ends of the two sets of grooves. To open the door 3 the 40 following procedure may be adopted; the knob or finger piece 14, preferably removably mounted for a reason that will hereinafter appear as by furnishing it with a screw threaded shank, is grasped and the 45 door swung forward. Initially or until the studs or pins 5 and 7 leave the first portion of the mating grooves 11, the motion of the door will be simply a swinging one. Beyond this point as the door is manipulated, 50 its upper portion is swung into the cabinet or case 2 and at the same time there is a slight lifting motion imparted by the cam portions of the two sets of grooves 10 and 11 until the door has practically reached 55 its extreme upward movement after which point the upward movement of the door is comparatively slight or until what might be considered in the illustration given, the lower cross bar of the door is practically 60 against the top of the cabinet 2 at which time the knob, presenting a suitable stop, acts against the cabinet or case 2 to prevent further inward movement of the door. To dismount the door the knob 14 is taken 65 from place and the two sets of pins pushed

out of the open inner ends 12 and 13 of the two pairs of grooves. There may be cases where one set of grooves and studs may be omitted.

It will be clear that my device comprises 70 a swinging member and a support therefor, the swinging member initially fitting within the support and having projecting studs arranged in pairs, the studs of the respective pairs being opposite each other and the 75 support having grooves arranged in duplicate pairs to slidably receive the respective pairs of studs, the forward ends of two of the duplicate grooves having bearings for two opposite studs and the forward portions of the other two grooves being shaped to positively prevent transverse and to permit solely swinging motion of the swinging member when the same leaves its initial position or when it substantially leaves said support, and the several grooves being shaped to jointly swing and move the swinging member transversely on thrust applied thereto, when said swinging member leaves said support. In the present 80 case the bearings in question are obtained by closing the forward ends of the grooves 8 and 10, so that on the primary movement of the swinging member 3, the studs 4 and 5 can turn against said closed ends at which 85 time the upper studs 5 and 7 travel in the forward arcuate portions 9' of the grooves 9 and 11. When I speak of transverse motion of the swinging member 3 I mean what would in the construction shown be a depth- 90 wise movement thereof.

What I claim is:

1. The combination of a swinging member and a support therefor, the swinging member initially fitting within the support 105 and having projecting studs arranged in pairs, the studs of the respective pairs being opposite each other and the support having grooves arranged in duplicate pairs to slidably receive the respective pairs of studs, the forward ends of two of the duplicate grooves having bearings for two opposite studs and the forward portions of the other two grooves being shaped to positively prevent transverse and to permit 110 solely swinging motion of the swinging member when the same leaves its initial position and passes substantially out of said support and the several grooves being shaped to jointly swing and move the swinging member transversely on thrust applied thereto, when said swinging member leaves 115 said support.

2. The combination of a swinging member and a support therefor, the swinging member having projecting studs and the support having grooves to slidably receive 125 said studs and shaped to jointly impart a camming and guiding action to said swinging member, the rear ends of said grooves 130

being open to permit dismounting of the swinging member, and an operating member on the swinging member for engaging the support when the swinging member is 5 wide open, said operating member being removably mounted.

In testimony whereof I affix my signature in presence of two witnesses.

HUGO V. STEUERNAGEL.
